ELECTRIC GUITAR

Charles A. Ross, 7th and S. Steuben,
Chanute, Kans. 66720

Filed Sept. 20, 1966, Ser. No. 3,936

Term of patent 14 years

(Cl. D56—1)

Fig. 1.

Fig. 2.

Fig. 3.

Fig. 4.

Fig. 5.

Fig. 6.

Fig. 7.

Fig. 8.

FIG. 1 is a top plan view of an electric guitar, showing one form of my new design wherein the surface of the guitar body is fluted parallel to the longitudinal axis of the guitar;

FIG. 2 is a side elevational view of the form shown in FIG. 1;

FIG. 3 is a bottom plan view of the form shown in FIG. 1;

FIG. 4 is an end elevational view of the form shown in FIG. 1;

FIG. 5 is a top plan view of an electric guitar, showing a second form of my new design wherein the body of the guitar is fluted perpendicular to the longitudinal axis of the guitar;

FIG. 6 is a side elevational view of the form shown in FIG. 5;

FIG. 7 is a bottom plan view of the form shown in FIG. 5;

FIG. 8 is an end elevational view of the form shown in FIG. 5;

FIG. 9 is a top plan view of an electric guitar, showing a third form of my new design wherein the surface of the guitar body is fluted oblique to the longitudinal axis of the guitar;

FIG. 10 is a side elevational view of the form shown in FIG. 9;

FIG. 11 is a bottom plan view of the form shown in FIG. 9; and

FIG. 12 is an end elevational view of the form shown in FIG. 9.

I claim:

The ornamental design for an electric guitar as shown and described.
